UNITED STATES PATENT OFFICE.

FREDERICK A. WATKINS, OF HIGHLAND PARK, ILLINOIS, ASSIGNOR, BY MESNE ASSIGNMENTS, TO WESTERN ELECTRIC COMPANY, INCORPORATED, A CORPORATION OF NEW YORK.

SELECTING APPARATUS.

1,183,923.

Specification of Letters Patent. Patented May 23, 1916.

Application filed September 30, 1909. Serial No 520,373.

To all whom it may concern:

Be it known that I, FREDERICK A. WATKINS, citizen of the United States, residing at Highland Park, in the county of Lake 5 and State of Illinois, have invented certain new and useful Improvements in Selecting Apparatus, of which the following is a full, clear, concise, and exact description.

My invention relates to apparatus and 10 mechanism for selecting and holding one of a series of contact positions under control of electromechanism in a manner characteristic of automatic telephone exchanges and various signaling systems.

15 The object of my invention is to reduce the number of independent current impulse transmitting devices necessarily employed to a number which is a fractional part of the number of selective or contact positions in 20 the selector.

25 My invention consists of a plurality of keys or key-buttons, each corresponding to a definite numeral or numerals, and circuit arrangement whereby each key automatically becomes a units' key, a tens' key, a hundreds' key, etc., as may be required of it, in the act of successively manipulating the keys. With my invention ten keys, that is 30 one for each digit or numeral of the decimal system of notation, or even a lesser member, will suffice to produce all the operations which are brought about by the customary elaborate keyboard commonly provided 35 with as many sets of ten keys each as there are digit places in the highest number to be provided for.

40 The several features of my invention may be more readily understood by reference to the accompanying drawings which disclose one arrangement for embodying the invention in a sender circuit for a semi-mechanical telephone system.

45 The said drawings comprise Figures 1, 2 and 3, which, taken in sequence, show diagrammatically so much of the system as is necessary for the understanding of the invention. It will be noted that Fig. 2 is a continuation of the circuits from the bottom of Fig. 1, and Fig. 3 is a continuation 50 of the circuits from the right-hand end of Fig. 2.

55 Referring to Fig. 1, the keyboard is there shown as provided with ten key-buttons or keys, 0, 1, 2, 3, 4, 5, 6, 7, 8 and 9, respectively corresponding to the ten digits of the

decimal notation. Said Fig. 1 also shows at A a subscriber's line terminating at the central office and also the operator's cord circuit C these circuit arrangements being of the usual well-known type. Associated with the cord circuit C are the lines L, L¹, over which it is designed to transmit pulsations of current by the manipulation of the key-buttons of the keyboard. The present invention relates to the apparatus and circuit arrangement for controlling the production of the signaling or selecting current which in the case illustrated is sent over the lines L, L¹. Since the invention as applied to a semi-mechanical telephone system is 60 not limited to use in connection with any particular type of selecting mechanisms for completing the connection with the called subscriber's line, the showing of the latter apparatus and circuit arrangement therefor, 65 which may be of the usual type, is omitted for the sake of conciseness and clearness.

In the particular embodiment of the invention shown in the drawings, the connection of the lines L, L¹ with the lines 10, 11 70 of the sender circuit is initially under the control of the relay 12, the circuit of which may be closed at contact 13 by the operator throwing the usual listening key in a direction opposite to the listening position thereof. The usual pulsator P may be employed 75 for transmitting selecting pulsations over the one or the other of the lines 10 and 11.

80 A plurality of senders S, S¹, S², S³, a thousands', a hundreds', a tens' and a 85 units' sender, respectively, one for each order of digits in the highest number which it is designed to be called, are employed for controlling the application of current from the pulsator. The sending mechanisms may 90 be of any desired type, those illustrated in the drawings being of the well-known step-by-step type having an arm 14 controlled by a motor magnet 15 and a holding magnet 16, the motor magnet stepping the arm over 95 a series of contact points any one of which may have its electrical condition predetermined by a key in the keyboard to stop the arm 14 at this predetermined point and thus 100 to control the duration or number of pulsations sent over the sending circuit by the pulsator P. In the particular mechanism 105 shown each sender is provided with ten contact points p, p¹, p², p³, etc., corresponding to the keys, 0, 1, 2, 3, etc. The contact 110

points are preferably arranged in two concentric rows of five points each, having each point in one row multiplied with the corresponding point in the other row. The 5 sender arm 14 in such case is provided with two contact brushes 19, 20, one for each row of contact points, each brush being connected to a separate lead.

The "wetting," that is in this particular 10 case the grounding, of any one of the contact points of a sender is effected by a series of grounding relays G, G¹, G², G³, G⁴, the required number of such relays being reduced when corresponding contact points of 15 the sender are multiplied together in the manner just described. Each group of grounding relays G, G¹, G², etc., has a lead common to all the relays of the group, by which the relays of each group receive current 20 through the contacts of a corresponding battery switching relay R, R¹ or R² of the group, this common lead of the thousands' sender S being designated by the reference numeral 21. Each battery switching 25 relay is adapted to switch the connection of the battery B from one group of grounding relays to the next group, that is from the group associated with the thousands' sender to the group associated with the hundreds' 30 sender and so on.

The completion of the circuit for each 35 relay of a group of grounding relays is made at the contacts of the corresponding key, 0, 1, 2, 3, etc. Upon the operation of a grounding relay of one group, the closure 40 of contacts due to the return of the operated key to its normal position completes the circuit of the corresponding battery-switching relay R, R¹ or R², as the case may be, and switches the battery to the next 45 succeeding group of grounding relays.

Each key, which may be of any desired 50 type adapted to operate contact springs controlling the associated circuits when depressed, is provided with a grounded contact spring or springs 22, and is further provided with a contact spring for each sender. Since in the particular system shown there are four senders, S, S¹, S², and S³, each key is provided with four of said 55 latter contact springs, those associated with the key 0 being designated a, b, c and d, respectively. Taking the first or 0 key, for example, its contact spring a is connected to a wire 23 which includes the actuating winding 60 of the corresponding relay associated with the thousands' sender S, that is relay G. In like manner the springs, b, c, and d are connected by similar leads to the relays G associated with hundreds', tens' and units' senders, respectively. In like manner the 65 contact springs a¹, b¹, c¹ and d¹ of key 1 are connected to the windings of relays G¹ associated with the several senders, and so forth.

Since I preferably multiple the contact point p with the contact point p⁵, the contact point p¹ with the contact point p⁶, etc., as above described, in order to reduce the number of grounding relays, I also multiple 70 the contact springs a, b, c and d of key 0 with the corresponding springs a⁵, b⁵, c⁵ and d⁵, respectively of key 5. In like manner the corresponding springs of keys 1 and 6, 2 and 7, 3 and 8, 4 and 9 are strapped together. 75

Each of the keys 0 to 9 inclusive is further provided with a contact spring, normally closing contact with a spring 22, that of key 0 being designated e. Referring to 80 the key 0, the spring e has connected thereto a wire 24, which leads to a wire 25. The wire 25 has a series of taps 26, 27, 28 and 29 including the normally open contacts g of the grounding relays G associated with 85 each of the senders S, S¹, S² and S³, said taps also including the actuating windings of the battery switching relays R, R¹, R² and R³, respectively. In like manner the remaining keys are associated with said battery switching relays through the contacts 90 of the grounding relays corresponding to the respective keys.

A resistance E and a like resistance E⁵ is introduced in the circuit of the wires connected to the springs e and e⁵, respectively, and a similar resistance arrangement is provided for the corresponding springs of the remaining keys, in order to control the operation of the battery switching relays, as 100 will hereinafter more fully appear.

In order to avoid the necessity for a separate relay for grounding each contact point of the selector, each grounding relay is caused to control multiple points on the 105 sender, and since this is the preferred arrangement it is the one illustrated in the drawings and hereinbefore described. Obviously such arrangement is not essential, but where employed the contacts of the keys 110 are correspondingly multiplied together as hereinbefore described. In such case, it becomes necessary to introduce means whereby the manipulation of the keys 5, 6, 7, 8 and 9 will not cause the selector arm 14 to 115 stop at the contact points corresponding to the multiplied keys 0, 1, 2, 3 and 4, respectively. Said means comprises the brush-relays T, T¹, T², T³ associated with the respective senders, which relays normally hold 120 closed the circuit of the brushes 19 of the respective senders, and which when energized break the circuits through the brushes 19 and close them through the brushes 20. The energization of each brush-relay is controlled by an extra contact spring f, f¹, etc., of the keys 5, 6, etc., respectively, as will 125 hereinafter more fully appear.

In order to more fully set forth the functions and operations of the mechanism and 130

circuit arrangement hereinbefore mentioned in detail, the complete putting through of a call will now be described.

Assume that the operator in answer to a call has inserted the answering plug of the cord into the jack and has ascertained the number of the party desired, as for example, number 2728. The operator then momentarily throws the listening key in a direction opposite to the listening position thereof, thus closing contact 13 and thereby completing the following path:—from ground, battery B^1 , contact 13, wire 30, which includes the winding of relays 12 and 31, and resting contact 33 of relay 32 to ground. This causes the energization of relays 12 and 31; and the operation of relay 12, by closure of its contact 38, substitutes battery B^2 for battery B^1 , thereby retaining relays 12 and 31 energized so long as contact 33 of relay 32 remains closed. Relay 12 furthermore breaks the contacts 34 and 35 and closes the contacts 36 and 37, thereby shifting the lines L and L^1 , leading to the selecting mechanism (not shown) from the connection with the cord circuit to connection with the lines 10 and 11, respectively, of the sending circuit. The relay 31 in operating applies current from grounded battery B to the feed wire 17, and incidentally lights the pilot lamp M . The retaining magnets 16 of the several senders are energized by current from the wire 17, and draw up their pawls preparatory to the operation of the arms 14 of the senders S , S^1 , S^2 and S^3 .

After the momentary throw of the listening key, as above described, the operator will proceed to write off the number 2728 by momentary successive depressions of the digit buttons 2, 7, 2, 8. The button first depressed, in this case the button 2, will act as a thousands' button. The depression of said button will break the contacts of the spring 22 with the spring e^2 and will close the contacts of springs a^2 , b^2 , c^2 and d^2 , thus connecting said springs to ground 58^1 . The closure of contact spring a^2 completes the following path:—from ground 58^1 , through contact springs 22, b^2 and a^2 , wire 41, actuating winding of relay G^2 , wire 21, back contact 42 of relay R to feed wire 17. This energizes the relay G^2 which closes its contacts g^2 and h^2 . The closure of the contact h^2 completes a locking circuit for relay G^2 from ground 43 through contact h^2 , locking winding of relay G^2 and wire 44, to the feed wire 17. The relay G^2 is thus locked up so long as current remains on the feed wire. The closure of contact h^2 of the relay G^2 also grounds the contact point p^2 of the sender S , such ground connection being traced from ground 43, through contact h^2 and lead 45 to the contact point p^2 . Although the wire 39 is still grounded through the closed contact spring e^1 of the button 7, the resistance E^1

is sufficient to prevent the operation of the battery switching relay R despite the fact that the following path therefor is closed, namely: from ground 58^1 , through contact springs 22 and e^1 of key 7, strapping connection 40 including the resistance E^1 , wire 39, contact g^1 of relay G^1 , wire 26 which includes the actuating winding of the relay R , to the feed wire 17. As long as the button 2 remains depressed the closure of this circuit will not operate relay R due to the fact that the cutting out of the resistance E^2 , which is in parallel with the resistance E^1 , by the opening of the contact spring e^2 , increases the resistance of the circuit, and the relay R does not, so long as the button 2 is depressed, receive sufficient current to cause the same to operate.

The return of the button 2 to its normal position closes the contact of spring e^2 , thus including the resistance E^2 in parallel with the resistance E^1 , and thus reducing the resistance in the above described circuit closed through relay R . The relay R now receives sufficient current to be operated and closes a locking circuit for itself at contact 45. The relay R also breaks contact 42 and closes contact 46, thus transferring the current of feed wire 17 from the lead 21 of the thousand set of grounding relays to the lead 47 of the hundreds set. This transfer of current from one set of grounding relays to the next succeeding set takes place only after the operation of a relay in the group of grounding relays associated with the sender corresponding to the order of digits for which a key has been operated. When the battery has thus been transferred from a group of relays, current can be applied solely to the relays of the sender corresponding to the portion of the call next under selection.

The closure of the circuit including the feed wire 17 and the wire 39 by the contact g^2 of the relay G^2 causes the energization of the relay 18, which thereupon closes contact 48, thereby applying pulsating current from the pulsator P over the following circuit: from ground through pulsator P , contact 48, armature and contact 53 of relay 52, stepping magnet 15 to the line 10, which, as before stated, is now connected to the line L leading to the selecting mechanism.

The operations involving the stepping forward of the sender arm 14 and the synchronous operation of the selector mechanism (not shown), and likewise the stopping of the sender arm as soon as it reaches the selected contact point, in this case the contact point p^2 , is well understood. In this particular instance, as soon as the brush 19 reaches the grounded contact point p^2 , the circuit is completed from said contact point through the brush 19, normally closed back contact 51 of the brush relay T , relay 52 to the feed wire 17. The consequent energiza-

tion of the relay 52 opens the contact 53 in the circuit of the stepping relay 15 and thereby discontinues the operation of said relay, causing the arm 14 to rest on contact 5 ^{p²}. The contact 54 of relay 52 is now closed preparatory to the application of pulsating current to the stepping magnet 15 of the next succeeding sender S¹.

It will be observed that although the point 10 p⁷ as well as the point p² of the sender S was grounded the former point was ineffectual to make any circuit by reason of the fact that the brush 20 did not reach it in its travel. Had the button 7, for example, been 15 depressed, instead of button 2, thus also grounding both the points p² and p⁷, the circuit through the brush 19, when said brush reached the point p², would have been open at the then open contact 51, as will be 20 presently described in connection with the selection of hundreds' digit 7 of the called number 2728.

After the return of button 2 to its normal position, the depression of the button 25 next to be operated, in the example given the button 7, will produce results similar to those produced by the button 2 with the added result, since the button is one of the last five of the series, of the operation of 30 the brush relay T. The operation of said relay T associated with the hundreds' sender S¹ is brought about by the closure to ground of the contact spring f² of the 35 button 7. Such spring f² is connected to a wire 55 leading to a wire 56, which includes the actuating winding of the relay T and which leads to the wire 47 now connected, as hereinbefore stated, to the feed wire 17. The consequent energization of 40 the relay T¹, in addition to closing a locking circuit for itself at contact 57, opens its contact 58 and closes its contact 59, thereby opening the circuit of the brush 19 and closing the circuit of the brush 20 of 45 the sender S¹. Although the contact point p² of the sender S¹ has been grounded by the manipulation of key 7, the circuit of the brush 19 and the relay 60 is open at the contact 58, and hence the arm 14 continues 50 its travel until the brush 20 reaches the "wet" point p⁷, whereupon the circuit is completed from the grounded point p⁷ through the brush 20, wire 61, the now closed contact 59, relay 60 to the feed wire 17. The relay 60 thereupon operates to open 55 the circuit of the stepping magnet 15 associated with the sender S¹, thus causing the arm 14 to stop at the contact point p⁷. The remaining operations due to the depression 60 of the button 7 are similar to those hereinbefore described in connection with the depression of the button 2, the switching relay R¹ in this case operating to transfer the 65 connection of the feed wire 17 to the next succeeding sender, that is, to the sender S².

The landing of the sender arm 14 of the units' sender S³ on a grounded contact point will perform the extra function of restoring the entire sending apparatus to its normal position, due to the fact that the energization of the relay 32 opens contact 33 in the circuit of relay 31, thus causing the de-energization of said relay 31 and the consequent opening of its contact through which the battery B is connected to the feed wire 75 17. The opening of the contact 33 of the line 30 likewise causes the de-energization of the relay 12 and the consequent closure of its contacts 34 and 35 through which the lines L, L¹ are again connected to the cord 80 circuit.

For the sake of clearness a simple embodiment of the invention in a semi-mechanical telephone system has been shown. It is obvious that it may be modified to 85 meet other conditions of a more complicated system, and also that the invention may find uses in connection with still other types of signaling systems.

While ordinarily ten keys, one for each 90 digit, would be employed, in practising my invention, it is obvious that the invention is not limited to such particular number. My invention merely provides means whereby not more than ten keys are required for 95 calling any desired number however many digit places such number may have.

While I have shown my invention as adapted more particularly for a semi-mechanical telephone system, it must not be 100 considered as restricted to the form shown, nor to semi-mechanical telephone systems of the type indicated, or any other type. On the contrary it may with advantage be adapted to any system wherein it is desired 105 to control the number and arrangement of impulses sent or received over the signaling circuit whether these impulses pertain to the setting of an indicator, the operation of a selector switch or the control of any other mechanism or mechanisms adapted to be variably set.

I claim:

1. In an electric signaling system, the combination with a keyboard having a plurality of keys, each representing a different digit or digits of the decimal system of notation, of a plurality of senders controlled by said keys, one sender being provided for each digit place of the highest number designed 115 to be signaled, means for associating all of said keys with all of said senders and for automatically changing said keys from association with one sender to association with the next succeeding sender upon each successive manipulation of a key in transmitting a continuous signal, and a signaling circuit associated with said senders.

2. In an electric signaling system, the combination with a keyboard having a plurality 115

of keys corresponding in number and designation to the several digits of the decimal system of notation, of a plurality of senders controlled by said keys, one sender being provided for each digit place of the highest number designed to be signaled, means for associating all of said keys with all of said senders said means providing means for automatically changing said keys from association with one sender to association with another sender.

10 automatically changing said keys from association with one sender to association with the next succeeding sender upon each successive manipulation of a key in transmitting a continuous signal, and a signaling circuit associated with said senders.

15. 3. In an electric signalling system, the combination with a plurality of keys each representing a different digit or digits of the

20 decimal system of notation, of a plurality of senders, one for each digit place of the highest number designed to be signaled, said senders having contact points corresponding to said keys, a group of relays associated with each of said senders, circuit arrangements whereby the operation of

25 ments whereby the operation of any one of said relays determines the electrical condition of a corresponding contact point on the sender, circuit arrangements for operatively associating said keys successively with each of said groups of relays and for 30 associating each key with a corresponding relay of the particular group with which the keys may be associated, and a signaling circuit controlled by said senders.

35 4. In an electric signaling system, the combination with a keyboard having a plurality of keys corresponding in number and designation to the several digits of the decimal system of notation, of a plurality of senders, one for each digit place of the high

40 senders, one for each digit place of the highest number designed to be signaled, said senders having contact points corresponding to said keys, a group of relays associated with each of said senders, circuit arrangements whereby the operation of any one of said relays determines the electrical condi-

and relays determines the electrical condition of a corresponding contact point on the sender, circuit arrangements for operatively associating said keys with each of said

50. associating said keys with each of said groups of relays and for associating each key with a corresponding relay of each group, said latter circuit arrangements also providing means for automatically changing said keys from association with

55 ing said keys from association with one group of relays to association with the next succeeding group of relays upon each successive manipulation of a key in transmitting a continuous signal, and a signaling circuit controlled by said senders.

60 5. In an electric signaling system, the combination with a plurality of keys each representing a different digit or digits of the decimal system of notation, of a plurality of senders, one for each digit place of the highest number designed to be signaled, said senders having contact points corresponding

to said keys, a group of relays associated with each of said senders, circuit arrangements whereby the operation of any one of said relays determines the electrical condition of a corresponding contact point on the sender, switching relays for changing said keys from operative connection with the group of relays associated with one sender to the group associated with the next succeeding sender, circuit arrangements whereby, upon the return of a manipulated key to its normal position, the switching relay associated with the sender under the control of said manipulated key is operated to transfer said keys to association with the next succeeding sender, and a signaling circuit controlled by said senders.

6. In an electric signaling system, the combination with a keyboard having a plurality of keys designated to correspond to the several digits of the decimal system of notation, said keys being multiplied in pairs of a plurality of senders, one for each digit place of the highest number designed to be signaled, said senders each having a plurality of contact points multiplied in pairs to correspond with said keys, circuit arrangements whereby the manipulation of one of said keys "wets" a pair of multiplied contact points on one of said senders, a brush relay for each sender controlled from said keys, circuits controlled by said brush relay for rendering the "wet" contact point corresponding to the manipulated key effective for controlling the operation of said sender and the other of said pair of "wet" contact points ineffective, and a signaling circuit controlled by said senders. 85 90 95 100

7. In an electric signaling system, the combination with a keyboard having a plurality of keys designated to correspond to the several digits of the decimal system of notation, said keys being multiplied in pairs, of a plurality of senders, one for each digit place of the highest number designed to be signaled, said senders each having a plurality of contact points multiplied in pairs to correspond with said keys, a group of relays associated with each of said senders, circuit arrangements whereby the operation of any one of said relays "wets" a corresponding pair of contact points on the sender, circuit arrangements for operatively associating said keys successively with each of said groups of relays and for associating each key with a corresponding relay of the particular group with which the keys may be associated, a brush relay for each sender controlled from said keys, circuits controlled by said brush relay for rendering the "wet" contact point corresponding to the manipulated key effective for controlling the operation of said sender and the other of said pair of "wet" contact points ineffective, and a signaling circuit controlled by said senders. 130

8. In an electric signaling system, the combination with a keyboard having a plurality of keys corresponding in number and designation to the several digits of the decimal system of notation, said keys being multiplied in pairs, of a plurality of senders, one for each digit place of the highest number designed to be signaled, said senders each having a plurality of contact points multiplied in pairs to correspond with said keys, a group of relays associated with each of said senders, circuit arrangements whereby the operation of any one of said relays "wets" a corresponding pair of contact points on the sender, a brush relay for each sender controlled from said keys, circuits controlled by said brush relay for rendering the "wet" contact point corresponding to the manipulated key effective for controlling the operation of said sender and the other of said pair of "wet" contact points ineffective, switching relays for changing said keys from operative connection with the group of relays associated with one sender to the group associated with the next succeeding sender, circuit arrangements whereby, upon the return of a manipulated key to its normal position, the switching relay associated with the sender under the control of said manipulated key is operated to transfer said keys to association with the next succeeding sender, and a signaling circuit controlled by said senders.
9. In a controlling apparatus for electric signaling systems, the combination with a single set of digit keys, of a plurality of senders adapted to be controlled by said keys, and means operated each successive time any one of said keys is depressed for associating said set of keys with successive ones of said senders.
10. In a controlling apparatus for electric signaling systems, the combination with a single set of digit keys, of a plurality of senders with one of which said keys are normally associated, and means operated upon the depression of any one of said keys for disassociating said set of keys and said sender and associating said set of keys with another of said senders.
11. In a controlling apparatus for electric signaling systems, the combination with a set of digit keys comprising a single key representing each digit, of a plurality of senders adapted to be controlled by said keys, and automatic means for associating said set of keys with one after another of said senders, upon the successive operation of any keys of said set.
12. In a controlling apparatus for electric signaling systems, the combination with a set of digit keys comprising a single key representing each digit, of a plurality of senders with one only of which said keys are normally associated, and automatic

means for associating said set of keys with another of said senders, the second sender being thus placed under the control of any one of the keys of said set.

13. In a controlling apparatus for electric signaling systems, the combination with a single set of digit keys, of a plurality of senders adapted to be controlled by said keys, and means operated in the operation of said keys for successively associating said set of keys with a different one of said senders and for placing said senders successively under temporary control of any key of said set each time a key is operated in the transmission of a continuous signal. 80

14. A selection controlling apparatus, comprising a set of keys, a plurality of groups of relays governed in common by said set of keys, and a controller associated with each group of relays and having a movable member, the position of which is determined by the operation of the associated group of relays. 85

15. A selection controlling apparatus comprising a set of keys, a group of relays governed by said set of keys, a controller associated with the group of relays and having terminals greater in number than said relays and also being provided with a movable contact member coöperating with the terminals, the extent of movement of said contact member depending upon the condition of the associated relays, and means controlled by certain of the keys for determining which of a plurality of terminals the operation of the relays shall render effective. 90

16. In apparatus of the character described, the combination of a selecting device including a movable element having a number of selective positions, means for controlling said element including an electromagnetic device and a compound circuit; independently movable electric impulse transmitters in number a fractional part of said selective positions, and means whereby the movement of a transmitter changes said circuit connections to provide a path for a succeeding impulse in said circuit, determines the position of said element and automatically restores normal circuit conditions. 105

17. In apparatus of the character described, the combination of a selecting device including a movable element having a number of selective positions, an electromagnetic controlling device for said element, a compound circuit therefor including a battery branch; independently movable electric impulse transmitters in number a fractional part of the number of selective positions, multiple arc electric connections for corresponding contacts of said transmitters, a circuit breaker in each such connection, an electromagnet for each such circuit breaker, and circuit connections for said magnets whereby the transmitter first oper- 115

ated breaks the circuit through its corresponding multiple connection in the other transmitter.

18. In a selecting apparatus, the combination of a movable element having a number of selective positions, a series of independently operative transmitters in number a fractional part of the number of selective positions, parallel electrical connections between corresponding contacts of a pair of said transmitters, a resistance in each such connection and means whereby the operation of one of said pairs is ineffective upon the operation of the other.
19. In a selecting apparatus, the combination of a rotating shaft, a radial arm thereon, a series of radial contact positions for said arm, a controlling magnet, a circuit therefor, a plurality of electromagnetic switches in said circuit, a series of independent impulse transmitters, in number a fractional part of said radial contact positions, and means whereby the first transmitted impulse shifts one of said switches to provide a path for a succeeding current impulse and

whereby said succeeding impulse stops the radial arm in a contact position.

20. In a selecting apparatus, the combination of a rotating shaft, a radial arm thereon, a series of fixed radial contacts arranged in concentric rows, two contacts carried by said arm in position to engage with said fixed rows of contacts, respectively, an electrical connection between a contact in one row and a corresponding contact in the other row, a controlling magnet for said radial arm, a series of impulse transmitters in number a fractional part of said fixed contacts, an electrical connection between a contact in one transmitter and a corresponding contact in the other, and means whereby one duplicate contact is rendered ineffective when the other is operated.

In witness whereof, I hereunto subscribe my name this 28th day of September A. D., 1909.

FREDERICK A. WATKINS.
